(57) **CLAIM**

The ornamental design for a decorator garden hose holder, as shown and described.

DESCRIPTION

FIG. 1 is a perspective view of the decorator garden hose holder of the invention;

FIG. 2 is a front view of the decorator garden hose holder of FIG. 1;

FIG. 3 is an enlarged right side elevational view of the decorator garden hose holder of FIG. 1, the left side elevational view being a mirror image thereof;

FIG. 4 is a rear view of the decorator garden hose holder of FIG. 1;

FIG. 5 is a perspective view of the decorator garden hose holder of FIG. 1 showing the storage compartment door in an open configuration;

FIG. 6 is a front view of the decorator garden hose holder of FIG. 1 showing the storage compartment door in an open configuration;

FIG. 7 is a rear view of the decorator garden hose holder of FIG. 1 showing the storage compartment door in an open configuration; and,

FIG. 8 is an enlarged right side elevational view of the decorator garden hose holder of FIG. 1 showing the storage compartment door in an open configuration; the left side elevational view being a mirror image thereof.
